LASTING MACHINE

Herman Schwabe, New York, N. Y.

Application September 19, 1950, Serial No. 185,614

10 Claims. (Cl. 12—1)

1

This invention comprises a new and improved lasting machine useful in the general field of shoemaking but particularly for cover lasting, that is to say, lasting the margin of a cemented binding strip about the edge of an insole or a platform sole.

The object of the invention is to provide a machine of this character which is more compact in its structure, more convenient for the operator, and more effective in its lasting function than machines heretofore available. To this end an important feature of the machine comprises the combination of feed rolls operating to engage the margin of the binding strip or the lasting margin of the upper as the case may be, a wiper roll acting on the margin as it leaves the feed rolls, and a flexible smoothing and ironing helix extending inwardly over the shoe bottom beyond the range of wiping action of the wiper roll whereby the margin is smoothed and ironed and its entire edge securely united to the sole. I have found that a wiper roll having a ribbed end surface is very effective for wiping the margin in over the sole edge, but in order to provide a compact structure and to locate the wiper roll close to the feed rolls where it is most effective, its diameter must be limited so that in some cases it may not cover the entire margin. Consequently I provide a flexible driven helix which extends transversely over the shoe bottom closely behind the wiper roll and which is of sufficient length to iron and smooth not only the portion of the margin which is wiped inwardly by the wiper roll, but also the inner edge of the margin which may lie beyond the range of the wiper roll. It is believed that this combination of wiper roll having an effective end surface and ironing helix having an effective longitudinal surface has not heretofore been available to the shoemaking industry.

Further features of the invention reside in the ironing helix. This may be advantageously constructed of spring wire close wound in a helix presenting a body which is stiff but capable of bending under substantial pressure so that it will conform accurately to the shape of the shoe bottom as presented by the operator and firmly pressed against it. Preferably and as herein shown, the helix is secured at one end to a driven spindle which extends an appreciable distance into the interior of the helix, thus rigidly and securely providing a driving connection thereto while permitting the body portion of the helix to yield as already explained.

These and other features of the invention will

2

be best understood and appreciated from the following description of a preferred embodiment thereof, selected for purposes of illustration and shown in the accompanying drawings in which:

- 5 Fig. 1 is a plan view of the machine,
- Fig. 2 is a fragmentary view of the gearing,
- Fig. 3 is a fragmentary sectional view on the line 3—3 of Fig. 4,
- Fig. 4 is a view in elevation showing the machine housing in section on the line 4—4 of Fig. 1,
- Fig. 5 is a plan view showing the relation of the instrumentalities of the machine to the shoe bottom,
- Fig. 6 is a detailed view of the ironing helix,
- 15 Fig. 7 is a plan view showing the bottom face of the wiper roll,
- Fig. 8 is a fragmentary view on an enlarged scale showing portions of the wiper roll and one feed roll,
- 20 Fig. 9 is a sectional view of the roll driving mechanism, and
- Fig. 10 is a fragmentary view of the machine in front elevation.

The illustrated machine will be described as it is utilized in the operation of cover lasting, that is to say, stressing the margin of a binding strip upwardly and smoothly over the edge of a sole, overwiping the margin on the shoe bottom and adhesively securing it thereto. This treatment of the margin of the binding strip corresponds to the treatment of the lasting margin of the upper in conventional lasting for which the illustrated machine may also be employed.

The relative position of the instrumentalities of the machine in respect to each other and to the shoe bottom is best shown in Figs. 4 and 5. There are four of these elements and they comprise a feed roll 10 having a corrugated surface provided with feed spurs 11 and being fast to the lower end of the vertical shaft 12 by which it is driven when the machine is in operation. Cooperating with the feed roll 10 is an idle feed roll 13 also having a corrugated surface and being mounted upon the lower end of a stub shaft 14, as indicated in Fig. 3. These two feed rolls are yieldingly urged together and grip between them the upstanding margin of the binding strip upon which they exert a positive feeding and gripping action. The surface of the idle roll 13 is circumferentially grooved to receive with clearance the spurs 11 of the feed roll 10.

Adjacent to the feed rolls 10 and 13 and immediately behind them in the direction of feeding movement is a wiper roll 15 having upon its lower end surface a spiral rib 16, as shown in

Fig. 7. This wiper roll is fast to the lower end of the vertical shaft 17, and like the feed rolls is fixed in its vertical position. The bottom or end surfaces of the three rolls described, and particularly of the idle roll 13, act as a height gauge determining the vertical position of the shoe bottom as it is presented for the lasting operation. The wiper roll 15 is located substantially in line with the common tangent of the feed rolls so that about half the area of its end surface overlaps the shoe bottom.

Immediately beyond and behind the wiper roll 15 is provided an ironing helix in the form of a close wound spring 18 fast at its inner end to a horizontal spindle 19 by which it is driven. The helix extends transversely over the shoe bottom in a direction substantially at right angles to its contour at the operating point. The spindle 19 completely fills and rigidly supports the inner end of the spring helix 18, as shown in Fig. 6, while leaving the remainder of the coil free to yield vertically and so accommodate itself to the angle, contour and height of the shoe bottom. The spring ironing helix is continuously driven by the spindle 19 in such direction that on account of its helical formation it tends to iron down the inturned margin of the binding strip, smooth down any wrinkles therein, and press it yieldingly and uniformly down upon the cement-coated bottom of the sole to which it is being lasted. The ironing helix is long enough to extend beyond the inner edge of the margin and so insures that the entire margin is ironed down and that none of it is left in uplifted condition.

From the foregoing description it will be seen that the upstanding margin of the binding strip is first engaged in substantially vertical position by the feed rolls 10 and 13, gripped securely so that the margin is snugly conformed to the contour of the sole, and fed forwardly in the direction of the arrow shown in Fig. 5. The feeding operation is positively carried out by the action of the spurs 11. As the margin of the binding strip leaves the feed rolls it is immediately turned inwardly over the shoe bottom by the wiper roll 15 and subjected to a substantial inward wiping draft by the action of the spiral rib 16. Upon passing beyond the wiper roll 15, the inturned margin is immediately engaged and subjected to a severe yielding pressure and ironing, thus concluding the lasting operation and leaving the margin of the binding strip securely and smoothly cemented to the insole or platform sole as the case may be.

The general construction of the machine and the means for driving and controlling its operating instrumentalities will now be described. The machine comprises a hollow column 20 to the upper end of which is secured the main head casting 21. To the rear end of the casting is hinged a cover 22 and to its forward end is secured a gear housing 23. The casting includes an internal motor bracket 24 to which through suitable fittings is secured a vertical motor 25. To the upper end of the motor shaft is secured a step pulley comprising a small sheave 26 and a larger sheave 27. The sheave 26 drives a V-belt 28 passing about a larger pulley 29 arranged to rotate on a vertical shaft 30 projecting upwardly from a branch of the motor fitting 24'. The pulley 29 is also a step pulley having a small sheave 31 about which passes a V-belt 32 driving a pulley 33. The pulley 33 is mounted on ball bearings to rotate about a vertical shaft 34

projecting upwardly from a part of the gear housing and best shown in Fig. 9. The lower face of the pulley 33 is a finished clutch face and cooperates with a clutch disk 35 having a tubular stem and being mounted to slide vertically upon the shaft 34. It is normally held upwardly in engaged position by a compression spring 36 which encircles the stem of the clutch disk and bears at its lower end upon the upper face of a drive gear 37. The clutch disk 35 is disengaged by a clutch rod 38 telescopically received within the shaft 34 and bearing at its lower end upon a cross pin 39. The drive gear 37 is formed as a part of the shaft 34 and the latter is slotted to receive with clearance the cross pin 39 and normally driven by it so long as the clutch disk 35 is rotated. The gear 37 has a downwardly projecting stub shaft 47 for which bearings are provided in a portion of the gear housing 23.

In order to disengage the clutch and bring the drive gear 37 to rest, an arm 40 is pivotally mounted upon the top of the gear housing and provided with a hardened contact stud 41 which is arranged to engage and depress the clutch rod 38 when the arm 40 is swung in a clockwise direction. At its free end the arm 40 is connected to a vertical rod 42 and the latter is connected through links 43, 44 and 45 to ears projecting from the motor bracket 24. A treadle rod 46 has an adjustable swivel connection with the intermediate link 44. It will be seen, therefore, that by depressing the treadle rod 46 the clutch rod 38 is depressed against the compression of the spring 36 and the clutch disk 35 separated from the clutch surface of the pulley 33. The spring 36 acts at all times to hold the drive gear down against the upper face of its underlying bearing.

The drive gear 37 meshes with a pinion gear 48 fast to the upper end of the vertical shaft 12 which carries the feed roll 10. The cooperating feed roll 13 is mounted for free rotation on the lower end of a stub shaft 14 carried by a rocker member herein shown as a bell-crank lever 49 having an arm which is normally disposed vertically and being mounted to swing about a horizontal pivot pin supported in an ear 50 projecting forwardly from the gear housing 23. The other arm of the lever 49 extends inwardly and is connected at its inner end to a tension spring 51 adjustably suspended from a bracket within the cover of the machine and acting at all times to urge the roll 13 toward the roll 10. This arm of the bell-crank lever is also connected by a pin 52 to the link 43 and accordingly depression of the treadle simultaneously separates the feed rolls 10 and 13 and interrupts the driving connection to the feed roll 10 and the wiper roll 15. While this condition exists the operator may conveniently present a shoe to the machine.

The spindle 19 which carries the flexible helix 18 is mounted in an auxiliary casing having a horizontal tubular portion 55 which merges into a vertical tubular portion 56. The casing also includes a web portion 54 in which are provided vertical slots receiving bolts 57 by which the auxiliary casing is secured to the gear housing 23. By loosening the bolts 57 the auxiliary casing and the parts mounted therein may be vertically adjusted within a limited range in order to bring the helix 18 to the most effective vertical position with respect to the wiper roll 15.

The spindle 19 is provided at its inner end with a bevel gear 58 meshing with a corresponding bevel gear 59 on the lower end of a vertical

shaft 60 which is provided with bearings in the vertical portion of the auxiliary casing. The shaft 60 carries at its upper end a pulley 61 about which passes a V-belt 62 driven by the larger sheave 21 at the upper end of the motor shaft. It will be seen, therefore, that the spring helix 18 is driven continuously at a high rate of speed. The adjustment provided for the auxiliary casing is well within the range of which the driving bolt 62 will accommodate itself.

The wiper roll 15 as shown in Fig. 8 is fast upon the lower end of the vertical shaft 17 journaled like the shaft 12 in the housing 23. A gear 53 fast upon the upper end of the shaft 17 meshes with the drive gear 37 as shown in Fig. 2. Consequently the wiper roll 15 is driven when the clutch disk 35 is engaged and is brought to rest simultaneously with the feed roll 10 upon depression of the treadle rod 46.

Having thus disclosed my invention and described in detail a preferred manner and mechanism for putting it into practice, I claim as new and desire to secure by Letters Patent:

1. A lasting machine comprising cooperating feed rolls rotatable about substantially parallel vertical axes for feeding and gripping the margin of a binding strip, one of said rolls having an end surface engaging the shoe bottom, a wiping roll adjacent to the feed rolls having a ribbed end surface for wiping the margin inwardly as it leaves the feed rolls, a flexible close wound spring extending transversely across the shoe bottom adjacent to the wiper roll, and means for rotating said spring about its axis.

2. In a lasting machine having cooperating feed rolls for advancing the updrawn margin of the work, a flexible ironing tool having a helical work engaging face and comprising a spindle and a close wound spring secured at one end to the spindle and projecting beyond the end of the spindle, the spring itself thereby being free to conform yieldingly to the bottom of a lasted shoe passed beneath it, rigidly mounted bearings for the spindle, and mechanism for driving the spindle and thus rotating the spring.

3. In a lasting machine, cooperating feed rolls for updrawing the cement-coated lasting margin of a binding strip with respect to a sole in a shoe bottom, a wiper roll adjacent to the feed rolls having an end wiping surface for wiping the margin inwardly over the sole edge, and a driven spring helix extending inwardly beyond the edge of the inwiped margin and beyond the range of wiping action of the wiper roll, whereby the margin is smoothed and ironed and its entire inner edge securely united to the sole.

4. In a lasting machine, cooperating feed rolls operating to grip the lasting margin of a binding strip and one of which is mounted for bodily movement, a wiper roll located in position to act on the margin as it leaves the feed rolls, a single drive gear for one of the feed rolls and the wiper roll, a clutch driving said gear, and treadle operated mechanism for simultaneously disengaging the clutch and separating the feed rolls.

5. In a cover lasting machine, a pair of feed rolls mounted on normally vertical shafts for engaging and advancing the lasting margin in updrawn condition, a wiper roll having an end wiping face and being located close behind the feed rolls with its axis substantially in line with

their common tangent, and a spring helix rotatable about an axis disposed transversely to and above the shoe bottom and close behind the wiper roll.

6. In a lasting machine, cooperating feed rolls operating to engage the lasting margin of a binding strip, a wiper roll located in position to act on the margin as it leaves the feed rolls, an ironing helix disposed transversely at the rear of said wiper roll, driving mechanism including a clutch in train with a feed roll and said wiper roll, and separate driving mechanism for said helix.

7. In a lasting machine, cooperating feed rolls, one having a fixed vertical axis and the other an angularly movable axis, a wiper roll, geared connections between the wiper roll and one of the feed rolls, a helix of close wound spring wire disposed transversely and adjacent to the wiper roll, a horizontal driving spindle therefor, a vertical shaft having a geared connection therewith, a pulley at the upper end of said shaft, a second shaft having a pulley and geared connections with one of the feed rolls, a motor, and separate belt connections between the motor and each of the pulleys above mentioned.

8. A cover lasting machine comprising a pair of cooperating feed rolls, a roll having an end wiping face located behind the feed rolls in the direction in which the work is fed by them, a rotary ironing tool located adjacent to the wiping roll, gear mechanism for simultaneously driving the following elements, viz. one of the feed rolls and the wiper roll, and treadle operated means for interrupting the operation of both of the said elements by the gear mechanism.

9. A cover lasting machine comprising a feed roll rotatable about a fixed axis, a cooperating feed roll mounted in a spring pressed rocker member, a wiper roll located behind the feed rolls in the direction of the work feed, an independently driven rotary ironing tool located adjacent to the wiper roll, gear mechanism connected to one feed roll and to the wiper roll, a clutch controlling said mechanism, and treadle operated means for simultaneously disengaging the clutch and swinging said rocker member to separate the feed rolls.

10. A cover lasting machine of the character described in claim 9 in which a single motor drives the ironing tool and the feed and wiper roll gear mechanism through separate trains of operating connections.

HERMAN SCHWABE.
